United States Patent Office

Des. 180,999
Patented Sept. 17, 1957

180,999

CLOCK

Gordon Florian, Bridgeport, Conn., assignor to Sunbeam Corporation, Chicago, Ill., a corporation of Illinois

Application December 31, 1956, Serial No. 44,354

Term of patent 14 years

(Cl. D42—7)

Fig. 1 is a front elevational view of a clock showing my new design;

Fig. 2 is a top plan view of Fig. 1; and

Fig. 3 is a partially sectioned side view of the clock taken along line 3—3 of Fig. 2.

The back of the clock is substantially plain.

I claim:

The ornamental design for a clock, as shown and described.
